United States Patent Office.

THOMAS VARNEY, OF SAN FRANCISCO, CALIFORNIA.

Letters Patent No. 62,983, dated March 19, 1867.

IMPROVED MACHINE FOR CONCENTRATING ORES.

The Schedule referred to in these Letters Patent and making part of the same.

TO ALL WHOM IT MAY CONCERN:

Be it known that I, THOMAS VARNEY, of the city and county of San Francisco, and State of California, have invented a new and improved Concentrator, designed to be used in concentrating pulverized ores; and I do hereby declare that the following is a full and exact description thereof, reference being had to the accompanying drawings, forming a part of this specification, in which—

Figure 1 is substantially a plan or top view; and

Figure 2 is substantially a central vertical section view—

Similar letters of reference indicating corresponding parts in the different figures.

The most important part of my invention consists of a disk, A, the upper surface of which declines from the centre outwardly at an angle of about two and a half degrees. The surface should be turned true in a lathe, and when in operation the plane of its periphery should be strictly horizontal or level. Around the periphery of the disk is the trough B, its bottom being depressed considerably below and its outer side extending somewhat above the upper surface of the disk. The surface of the disk, as well as the trough, is divided, except at the centre, into eight equal compartments by the radial partitions C. At each extremity of each compartment of the trough is a hole through the bottom of the trough. The holes at one extremity, at D, I call metal holes and those at E I call refuse holes. The metal holes are furnished with thimbles adjustable vertically. The disk and trough are supported by the ribs F radiating from the hub G, in which is fixed the vertical shaft H, with its lower end stepped into the box I and its upper end held by the journal box J in the stand K. The stand K rests upon and is bolted to the cross-timbers L, halved together at the centre. Between the arms of this cross is laid the floor M declining inward. U^a is an arm projecting from the disk. O is a cam or ratchet-wheel, carried by the shaft P and pulley Q. R is a solid stop, against which the projection U^a strikes. S is a spring pressing the projection U^a against the stop R. At the centre of the disk is the hollow cone or distributor T. V is a funnel, the lower end of which fits the shaft H, by which it is supported, with holes through it below the top of the hollow cone T.

The operation is as follows: The ratchet-wheel O being revolved, one of its teeth gradually presses the arm U^a back against the spring S until the tooth escapes the arm, when it (the arm) is thrown suddenly forward by the spring against the solid stop R, carrying the disk with it. Now let the material to be concentrated, consisting of pulverized ores, be mingled with water and turned in a steady stream into the funnel V. The pulp passes through the holes in the funnel into the hollow cone T and flows over its top at all points equally and runs down upon the several compartments of the disk. As the pulp descends it spreads and the water washes along and carries off the lighter and worthless particles of the ore into the trough B, and thence along the trough to and through the refuse holes E and pipes W into the waste drain X, while the heavier particles containing metal are gathered up against the partitions on the side of the compartments, where the metal holes D are, and gradually work down the disk into the metal holes and thence into the receptacles Y. The reason of this gathering of the heavier particles to the metal holes is this: On account of their superior weight, the heavy particles do not move easily. The steepness of the disk and the current of water are such as to just fail in running them off, but sufficient to run off the light particles. Neither does the gentle movement of the disk against the spring disturb the heavy particles, nor its movement with the spring, until the occurrence of the shock against the stop, when they are shot forward, by their momentum toward the metal hole side. Again, while the heavy particles are at rest on the disk the current does not affect them, but as soon as they receive the lateral motion from the shock the current is enabled to move them downward, so that their resultant motion or true line of travel is diagonal toward the metal holes. The tops of the thimbles should be a little higher than the adjacent surface of the disk. The effect of elevating the thimbles, other things being equal, is to increase the purity of the portion of the ore concentrated, and *vice versa*. All the metallic particles do not go directly to the metal holes, as above described, but some of them, especially the lighter ones, get into the trough, where they arrange themselves so as to form an inclined plane from the top of the thimbles toward the refuse hole, down which the water and lighter particles float and up which the metallic particles work themselves into the metal holes.

It is impossible to give definite directions as to the speed, or throw of the cam, or tension of the spring, or height of the thimbles, or rapidity of feed, or relative proportion of ore and water proper to secure the best results in concentrating ores of different kinds and degrees of fineness, but all these things can be easily regulated by observing the operation of the machine and its results.

Having thus described my invention, what I claim as new, and desire to secure by Letters Patent, is—

1. The use of the disk A, divided into compartments.
2. The trough B, all constructed in the manner and for the purposes set forth.

THOMAS VARNEY.
